UNITED STATES PATENT OFFICE

155,926

DESIGN FOR A COAT HANGER

Jacob I. Robin, New York, N. Y.

Application February 7, 1948, Serial No. 144,340

Term of patent 3½ years

(Cl. D80—8)

To all whom it may concern:

Be it known that I, Jacob I. Robin, citizen of the United States, residing at New York, in the county of New York and State of New York, have invented a new, original, and ornamental Design for Coat Hanger, of which the following is a specification, reference being had to the accompanying drawing, forming part thereof.

I claim:

The ornamental design for a coat hanger, as shown.

JACOB I. ROBIN.
